Apparatus and method for separating materials having different specific gravities, such as a wax-oil mixture, for example, and the like.

UNITED STATES PATENT OFFICE

2,534,210

CENTRIFUGAL SEPARATION

August Henry Schutte, Hastings on Hudson, N. Y., and Ward F. O'Connor, Bayonne, N. J.; said O'Connor assignor to The Lummus Company, New York, N. Y., a corporation of Delaware.

Application February 28, 1946, Serial No. 650,792

6 Claims. (Cl. 233—11)

1

This invention relates to centrifugal separation of a mixture of materials having different specific gravities, such as a wax-oil mixture, for example.

U. S. Patent No. 2,168,306, issued to A. H. Schutte, August 1, 1939, and entitled "Method of Separating Wax," discloses a wax-oil separation process wherein the wax-oil mixture, prior to introduction thereof to a centrifuge, is emulsified with a non-solvent liquid such as water, for example, and an inert gas, such as air.

U. S. Patents Nos. 2,394,015 and 2,394,016, both issued to A. H. Schutte and A. W. Mack, February 5, 1946 and both entitled "Centrifugal Separation," further disclose provision for sufficient residence time of the mixture within a centrifuge of the solid-bowl type, to obtain more complete separation of the oil and wax, and provision for discharge of the oil and the non-solvent liquid of the emulsion from the centrifuge in a manner to prevent discharge of wax therewith. More particularly, said patents disclose provision for discharge of completely separated wax from a point within the centrifuge spaced radially inward from the circumferential wall of the centrifuge, provision for discharge of the oil and the non-solvent liquid, completely separated from the wax, from a point within the centrifuge located between said wall and said point of wax discharge and also provision for retention of a layer of the oil and submerged wax in a radial position between said discharge points in order to prevent discharge from said layer.

to bring them back to this original position to

An important object of the present invention is to provide for preparation and delivery of the emulsion charge to the centrifuge in an improved manner to obtain more conveniently and reliably the advantages taught by the disclosures of the aforesaid patents. A further object of the invention is to provide for automatic control of the charging of the centrifuge in a manner to ensure retention of the layer of oil and submerged wax in a radial position within the centrifuge between the discharge point of the separated wax and the discharge point of the liquid separated from the wax.

A still further object of the invention is to provide, in a centrifuge, an improved structure for effecting the said discharge of the wax and the separated liquid from radially spaced points.

These and other objects and advantages of the invention will appear from the following description taken in connection with the accompanying drawing.

It is an object of the present invention to provide an improved centrifuge and improved charging system therefor, the centrifuge being shown in vertical section and the illustration of the charging system being partly diagrammatic; and

It is another object of the present invention to provide an improved structural detail of the centrifuge, upon a larger scale than Fig. 1.

2

In the drawing:

Fig. 1 is a view of the improved centrifuge and the improved charging system therefor, the centrifuge being shown in vertical section and the illustration of the charging system being partly diagrammatic; and

Fig. 2 is a vertical sectional perspective view of an improved structural detail of the centrifuge, upon a larger scale than Fig. 1.

According to the invention, air and water or other suitable liquid, non-solvent with respect to the oil and the wax, are continuously delivered to the wax-oil mixture prior to introduction of the mixture to the centrifuge and the mixture with the added liquid and air are subjected to a mixing operation to form an emulsion. A portion of the added water is obtained from a source outside of the charging system and its temperature is sufficiently low to chill and solidify the wax component of the mixture for efficient separation of the wax from the liquid components of the charge by centrifuging. Another portion of the added water is obtained from the liquid discharged from the centrifuge. Said discharge comprises oil and water separated from the wax. The water of the discharge, or a substantial portion thereof, is separated from the oil by settling and supplied in an amount required to the centrifuge charge to supplement the supply of said temperature-conditioning water of the charge. In the course of charging the centrifuge the supply of temperature-conditioning water is varied to satisfy temperature-conditioning requirements, and the supply of the said separated water is varied to compensate for the variations in the supply of the temperature-conditioning water and maintain a substantially uniform combined delivery of temperature-conditioning water and separated water to the centrifuge. Since the separated water has been previously temperature-conditioned by employment in the charging and centrifuging steps, addition thereof to the charge does not interfere with the temperature-control obtained through variation of the amount of temperature-conditioning liquid delivered to the charge.

The maintenance of a substantially uniform combined delivery of the temperature-conditioning water and the separated temperature-conditioned water to the centrifuge is for the purpose of retaining a layer of incompletely separated components of the charge in a desired radial position within the centrifuge. This layer comprises oil with a portion of the wax cake submerged therein. The centrifuge is devised to

discharge the wax from a point spaced radially inward from the circumferential wall of the rotor and to discharge the oil and water, separated from the wax, from a point radially located between said wax discharge point and said wall. By maintenance of a certain correlation of the said combined delivery and the liquid discharge capacity of the centrifuge for a given rate of rotation of the latter the said layer of oil and wax is retained in a radial position between the points of discharge of the separated liquid and the separated wax. Thereby, discharge of wax with the liquid and liquid with the wax is prevented.

According to the invention, the delivery of temperature-conditioning water and the delivery of temperature-conditioned water for compensating effect are both automatically controlled. The invention provides a system for preparing the charge and delivering it continuously to the centrifuge and the system includes temperature-responsive means to vary delivery of the temperature-conditioning liquid to the charge as required and also means responsive to such variation to vary delivery of the temperature-conditioned water in order to maintain automatically a substantially uniform combined delivery. The invention also provides for alteration of said uniform combined delivery and also for alteration of the liquid discharge capacity of the centrifuge and for changing the radial position of the wax discharge point.

The centrifuge employed is of a solid-bowl type as distinguished from the filtering type. In the present instance, the bowl or rotor 1 of the centrifuge has a cylindrical, imperforate circumferential wall and an imperforate bottom wall. A shaft 2 is affixed to the bottom wall, for rotation of the bowl, and may be driven from any suitable power source, not shown. A flat, annular baffle 3 is secured to the bottom of the bowl in a position spaced upwardly therefrom and is disposed concentric to the axis of the bowl, with its outer edge spaced from the surrounding circumferential wall of the bowl. At the upper end thereof, the bowl has an inwardly extending annular lip 4. In the present instance, this lip comprises an annular outer section 4a of frustoconical form and a flat annular inner section 4b detachably secured to the outer section, as by screws 5, and extending radially inward from the outer section. The outer section has an outwardly turned base flange 6 detachably secured, as by screws 7, to a flange on the upper edge of the bowl. This outer lip section has, intermediate its radial width, a circular series of apertures 8 all equidistant from the axis of the bowl and spaced radially inward from the circumferential wall of the bowl. These apertures serve as discharge ports for liquid separated from the wax, and the inner edge of the lip section 4b defines an outlet for discharge of completely separated wax from the centrifuge.

A cylindrical housing 9 substantially encloses the centrifuge bowl. Within the upper portion of the housing, there is an annular member 10 having an upstanding wall and an outwardly extending wall joined to the surrounding wall of the housing and forming therewith a trough 11 to receive the wax discharged from the bowl. A pipe 12 provides for withdrawal of the wax from the trough. At the upper edge thereof, the trough-forming member 10 has an annular flange 10a extending radially inward to overlie the apertures 8 of the bowl lip. This flange is disposed below the level of the lip section 4b. The circum-

ferential wall of the housing has a surrounding upper jacket 13 at the level of the trough 11, and a surrounding lower jacket 14 extending from the jacket 13 to the lower end of the housing. The upper jacket is supplied with steam to liquefy the wax within the trough by indirect heat exchange, and water is passed through the lower jacket to temperature-condition the lower zone of the housing and its contents. A pipe 15 leads from the bottom of the housing to conduct therefrom water and oil discharged from the centrifuge bowl. This pipe delivers to a settling tank 16 within which at least a portion of the water settles from the oil. The oil and the remainder of the water are withdrawn from said tank by a pipe 17 and a pump 18.

The system for continuously preparing the charge and continuously delivering it to the centrifuge includes a pipe 19 provided with a pump 20 and through which the wax-oil mixture or other mixture to be separated is supplied. A pipe 21 is connected to pipe 19, at the delivery side of the pump 20, to deliver to the mixture air under pressure. Pipe 21 has a valve 22 to control said air delivery. Another pipe, 23, is connected to the pipe 19 for delivery thereto of water or other suitable non-solvent liquid for emulsification with said mixture and also for temperature-conditioning the mixture. Pipe 23 leads from a source, not shown, of non-solvent liquid. En route to the pipe 19, the non-solvent liquid within the pipe 23 is supplied as required with temperature-conditioned water from the settling tank 16. A pipe 24 leads from the bottom of tank 16 to the inlet of a pump 25 to conduct the settled-out water thereto, and said pump delivers said water through a pipe 26 to the pipe 23. Pipe 19 is in delivery connection with a mixing or emulsifying device to pass thereto the combined charge of wax and oil and the water delivered through the pipes 23 and 26. As indicated, the emulsifying device may comprise a rotary pump 27 having a discharge pipe 28 and a recycle pipe 29 leading from the pipe 28 back to the pipe 19, at the inlet side of the pump. A manually adjustable pressure control valve 30 is connected to the pipe 28, beyond the point of connection of the recycle pipe thereto. From the valve 30, a pipe 31 leads to the centrifuge to deliver thereto the emulsified charge. Preferably, as shown, pipe 31 extends downwardly within the centrifuge bowl, along the axis of the bowl, and is formed to discharge the emulsion into the space between the annular baffle 3 and the bottom of the bowl.

Provision is made for automatic control of delivery of water through the pipe 23 in accordance with temperature-conditioning requirements of the charge within pipe 28. For that purpose, pipe 28 is provided with a thermostat 32 operatively connected, as at 33, with a thermostatic device 34. The latter is, in turn, operatively connected, as at 35, with a valve 36 in the pipe 23 so that temperature variation of the charge within pipe 28 will cause operation of the valve to increase or decrease the delivery of temperature-conditioning water as required to maintain the charge at a required temperature.

Provision is also made for automatic control of delivery of temperature-conditioned water to the charge in order to maintain a substantially uniform combined delivery of the water supplied through the pipe 23 and that supplied through the pipe 26. For that purpose, pipe 23 is provided with an orifice device 37 located between the point of connection of pipe 26 with the pipe 23

and the connection of pipe 23 with pipe 19. The orifice device is operatively connected, as indicated at 38, with a flow control device 39. The latter device is operatively connected as at 40, with a valve 41 in the pipe 26 so that variation in delivery of water through the orifice device will cause actuation of the device 39 to operate the valve 41 to increase or diminish delivery of water through the pipe 26 in order to compensate for fluctuations in volume of water delivery through pipe 23. The flow control device 39 is adjustable by means of knob 39a to select a desired maximum delivery of water through the pipe 26. The thermo-responsive device 34 is also adjustable by means of a knob 34a for maintenance of a selected temperature of the charge.

The thermo-responsive device 34, the orifice device 37, and the flow control device 39 may be of standard types. Their specific constructions form no part of the present invention and detailed illustration and description thereof is omitted in order to simplify the disclosure. The device 34 may be of a type known as a "Recording temperature controller" and the device 39 may be of a type known as a "Recording flow controller."

In the operation of the separating apparatus, the wax-oil or other mixture to be separated is continuously delivered by the pump 20 through the pipe 19 to the emulsifying device 27 along with air continuously delivered to the pipe 19 through the pipe 21 and water delivered through the pipe 23. The combined charge of wax-oil mixture, air and water is recycled as required through the pipe 29 to the emulsifying device, and the pressure control valve 30 maintains a required pressure within the emulsifier to obtain the desired degree of emulsification. Through the pipe 31, the emulsion is continuously delivered to the centrifuge bowl and discharged beneath the baffle 3. Said baffle directs the charge radially outward to the circumferential wall of the bowl and the charge then flows upwardly through the narrow annular space between said wall and the outer edge of the baffle and into the separating zone above the baffle. There, the charge is separated by centrifugal force into concentric layers including a layer W of water, a layer O of oil, a layer S of oil with wax cake submerged therein and a layer C of wax cake, said layers being named in the order of their approach to the centrifuge axis.

As previously mentioned, and as disclosed in the aforesaid patents of Schutte and Mack, it is desired that only the water and oil from the layers W and O be discharged through the apertures 8 of the bowl lip 4, that only the separated wax from the layer C be discharged past the inner edge of the lip and that the intermediate layer S of oil and submerged wax cake be retained in a radial position between said apertures and the inner edge of the lip. The present invention provides for automatic retention of the layer S in that position by automatic control of the volume of water delivered with reference to the speed of operation and the discharge capacity of the centrifuge through the lip apertures 8. Thereby, the desired thickness of the water layer W is retained to radially position the layer S properly and prevent discharge therefrom through either of said outlets. At the same time, the invention preserves proper temperature control by the employment of previously used, and therefore temperature-conditioned, water as make-up to com-

pensate for variation in delivery of temperature-conditioning water to the charge.

The delivery of temperature-conditioning water through the pipe 23 is made subject to the temperature of the emulsion charge within the pipe 23. A rise in temperature of the charge above that required causes actuation of the thermo-responsive device 34 to operate the valve 36 for increased delivery of water through the pipe 23. A reduction in temperature of the charge below that required causes actuation of the device 34 to operate the valve 36 for a required reduction in delivery through the pipe 23. In response to such fluctuation in delivery through the orifice device 37, the flow control device 39 is actuated to cause operation of the valve 41 for increased or decreased delivery of temperature-conditioned water as required to maintain the combined delivery of water by the pipes 23 and 26 substantially uniform.

The water for delivery through the pipe 26 is obtained from the layer W within the centrifuge. Water and oil together are discharged from the layers W and O respectively through the lip apertures 8. The flange 10a of the annular trough-forming member 10 serves as a baffle to deflect such discharge downwardly to the bottom of the housing 9. There, said discharge is collected and conducted by the pipe 15 to the settling tank 16. Water settles from the oil within said tank and is delivered to the supply pipe 23 by the pipe 24 and the pump 25.

Since the lip 4 of the centrifuge bowl is detachably secured to the bowl and is formed of the detachable sections 4a and 4b the radial location of the discharge point for the wax and the radial location and the discharge capacity of the apertures 8 may be varied to suit different charges and different operating conditions. The lip section 4b may be readily detached and replaced by another section of different internal diameter, and the outer section 4a may also be detached and replaced by one having a different number of the apertures 8 or having apertures of different size or different radial location. In cooperation with this adjustment feature, the flow control device 39 may be readily adjusted by means of its knob 39a to adjust the maximum water feed with relation to a particular adjustment of the points of discharge from the centrifuge bowl.

While the invention is described as employed for the separation of a wax-oil mixture, it is well adapted for use in the separation of other liquid-solid mixtures and also for separation of purely liquid mixtures.

It is, of course, to be understood that the present disclosure of our invention is merely illustrative and in nowise limiting and that the invention comprehends such modifications as will come within the scope of the following claims.

We claim:

1. Separating apparatus, comprising a centrifuge of the solid-bowl type operable to separate a fluid mixture of materials of different specific gravity; and a charging system for said centrifuge comprising a mixing device, means including a conduit for delivery of said mixture to the mixing device, a conduit for a temperature-conditioning liquid in delivery connection with the mixing device, means including a conduit for passing to the mixing device separated liquid discharged from the centrifuge, a main charge conduit arranged to conduct from the mixing device to the centrifuge the combined mixed

charge including the said mixture, the temperature-conditioning liquid and said separated liquid, means responsive to variation in the temperature of said combined charge within the main charge conduit to control delivery of the temperature-conditioning liquid through its said conduit, and means responsive to variation in delivery of said temperature-conditioning liquid through its conduit to control delivery of the separated liquid through its said conduit, to cause substantially uniform combined delivery to the centrifuge of the temperature-conditioning liquid and said separated liquid.

2. A charging system for a centrifuge of the solid-bowl type, comprising a mixing device, means including a conduit in delivery connection with said mixing device to pass thereto a fluid mixture of materials to be separated by the centrifuge, a conduit for a temperature-conditioning liquid in delivery connection with the mixing device, a conduit for a temperature-conditioned liquid in delivery connection with the mixing device, a main charge conduit leading from the mixing device to conduct to the centrifuge a combined mixed charge including said mixture, said temperature-conditioning liquid and said temperature-conditioned liquid, means responsive to variation in temperature of said combined charge within said main charge conduit to control delivery of the temperature-conditioning liquid through its said conduit, and means responsive to variations in delivery of the temperature-conditioning liquid through its said conduit to control delivery of the temperature-conditioned liquid through its said conduit, to cause a substantially uniform combined delivery to the centrifuge of the temperature-conditioning liquid and the temperature-conditioned liquid.

3. A charging system for a centrifuge of the solid-bowl type, comprising a main charge conduit for delivery association with the centrifuge, means including a conduit in delivery connection with said main conduit to pass thereto a fluid mixture of materials to be separated by the centrifuge, a conduit for a temperature-conditioning liquid in delivery connection with said main conduit, a conduit for a temperature-conditioned liquid in delivery connection with said main conduit, means responsive to variation in temperature of the combined charge of said mixture, said temperature-conditioning liquid and said temperature-conditioned liquid within the main conduit to control delivery of the temperature-conditioning liquid through its said conduit, and means responsive to variation in delivery of the temperature-conditioning liquid through its said conduit to control delivery of the temperature-conditioned liquid through its said conduit, to cause a substantially uniform combined delivery to the centrifuge of the temperature-conditioned liquid and the temperature-conditioning liquid.

4. A charging system for a centrifuge of the solid-bowl type, comprising a main charge conduit for delivery association with the centrifuge, means including a conduit in delivery connection with said main conduit to pass thereto a fluid mixture of materials to be separated by the centrifuge, a conduit for a temperature-conditioning liquid in delivery connection with said main conduit, a conduit connected to the second-mentioned conduit to deliver thereto temperature-conditioned liquid for passage to the main conduit along with the temperature-conditioning liquid, an orifice device in the second-mentioned

conduit and located for flow of both of said liquids therethrough, means responsive to variation in temperature of the combined charge of said mixture, said temperature-conditioning liquid and said temperature-conditioned liquid within the main conduit to control delivery of the temperature-conditioning liquid through its said conduit, and means responsive to variation in flow through said orifice device consequent to variation in said delivery of the temperature-conditioning liquid to control delivery of the temperature-conditioned liquid through its conduit, to cause a substantially uniform combined delivery to the centrifuge of the temperature-conditioning liquid and the temperature-conditioned liquid.

5. Separating apparatus, comprising a centrifuge of the solid-bowl type operable to separate a charge mixture of a liquid and a lighter material and having an outlet disposed for discharge of the separated lighter material from a point spaced radially inward from the circumferential wall of the centrifuge and having also an outlet disposed for discharge of separated heavier liquid from a point radially located between said wall and said first outlet; and a charging system for said centrifuge, comprising a mixing device, a conduit in delivery connection with said device to pass the charge thereto, a conduit in delivery connection with said mixing device to conduct a temperature-conditioning liquid thereto and having a valve, a recycle conduit connection to conduct said heavier liquid discharged from the centrifuge back to the centrifuge and also having a valve, a main charge conduit forming part of said recycle connection and arranged to conduct from the mixing device to the centrifuge the combined charge of said mixture, the temperature-conditioning liquid and the recycled liquid, a thermo-responsive device operatively connected to said valve of the conduit for the temperature-conditioning liquid and responsive to variation in temperature of said combined charge within the main conduit to control delivery of the temperature-conditioning liquid through its conduit, a flow control device operatively connected to said valve of the recycle connection and responsive to variation in said delivery of the temperature-conditioning liquid to control delivery through the recycle connection and cause substantially uniform combined delivery to the centrifuge of the temperature-conditioning liquid and the recycled liquid for regulation of the said discharge of the separated materials.

6. Separating apparatus, comprising a centrifuge of the solid-bowl type operable to separate a charge mixture of a liquid and a lighter material and having an outlet disposed for discharge of the separated lighter material from a point spaced radially inward from the circumferential wall of the centrifuge and having also an outlet disposed for discharge of separated heavier liquid from a point radially located between said wall and said first outlet; and a charging system for said centrifuge, comprising a main conduit for the charge in delivery connection with the centrifuge, a conduit in delivery connection with said charge conduit to conduct temperature-conditioning liquid thereto and having a valve, a recycle conduit connection arranged to conduct said heavier liquid discharged from the centrifuge back to the centrifuge and also having a valve, a thermo-responsive device operatively connected to said valve of the conduit for the

temperature-conditioning liquid and responsive to variation in temperature of the charge within the main conduit to control delivery of the temperature-conditioning liquid through its conduit, a flow control device operatively connected to said valve of the recycle connection and responsive to variation in said delivery of the temperature-conditioning liquid to control delivery through the recycle connection and cause substantially uniform combined delivery to the centrifuge of the temperature-conditioning liquid and the recycled liquid and regulation of the said discharge of the separated materials.
